Attorney.

UNITED STATES PATENT OFFICE.

ARTHUR G. MCKEE, OF CLEVELAND, OHIO.

GAS-BURNER.

967,417.

Specification of Letters Patent. Patented Aug. 16, 1910.
Application filed April 8, 1909. Serial No. 483,605.

To all whom it may concern:

Be it known that I, ARTHUR G. MCKEE, a citizen of the United States, resident of Cleveland, county of Cuyahoga, and State 5 of Ohio, have invented a new and useful Improvement in Gas-Burners, of which the following is a specification, the principle of the invention being herein explained and the best mode in which I have contemplated 10 applying that principle, so as to distinguish it from other inventions.

My invention relates to gas burners, and particularly to that class of burners used for delivering the necessary gas for producing 15 the heat such as is required in boilers and the like.

The object of my invention is to produce a burner of the above described character which will be economical in its construction 20 and efficient in its operation.

The said invention consists of means hereinafter fully described and particularly set forth in the claims.

The annexed drawing and the following 25 description set forth in detail certain means embodying the invention, the disclosed means, however, constituting but one of various mechanical forms in which the principle of the invention may be applied.

30 In said annexed drawings:—Figure 1 is a vertical axial section of a gas burner embodying my invention, together with a broken section of a gas main to which such burner is attached, a sectional portion of the 35 boiler being also shown in connection therewith. Fig. 2 is an elevation of the mechanism shown in Fig. 1.

The apparatus as illustrated in the drawings consists of three principal parts, the 40 valve-casing, the valve and valve-actuating mechanism, and the nozzle. The casing A is secured to the main B by means of an intermediate connection A', which for the purpose of this application, may be considered 45 a part of the valve-casing. Secured between the casing A and the connection A' is a ring A² formed with a circular opening which constitutes the valve-opening. That part of the ring A² upon the lower edge 50 thereof and surrounding the opening constitutes the valve seat and the parts are so arranged as to cause this seat to assume a horizontal position, as shown.

Arranged so as to be movable vertically 55 and to engage the valve seat from below is a bell-valve C, which is formed with an upper

surface c inclining from its central portion downwardly and outwardly toward the periphery of the valve, such inclined surface terminating at such periphery. The valve 60 is supported upon a stem C', which passes through a bushing a forming part of the casing. The lower end of the valve stem is threaded and the diameter of the bore in the bushing is made substantially equal to the 65 outer diameter of the threads, the diameter of the cylindrical portion of the stem being also equal to the diameter of such bore. It will therefore be noted that the stem may slide vertically in the bushing. Suitable 70 grooves a' are provided in the bushing which form an air or gas packing, such as is well known, and used for like purposes. A feather a² is fixed to the bushing and extends horizontally into an elongated slot c', 75 shown in dotted lines in Fig. 2. This feather prevents the stem C' from turning when it is moved longitudinally in the bore of the bushing.

The lower end of the stem is made of a 80 length sufficient to project some distance out of the bushing and such projecting portion is engaged by a nut C² provided with a hand wheel C³. It will therefore be seen that by turning the hand wheel, and consequently 85 the nut, the valve-stem and the valve may be moved in the direction of their common axis, and the valve therefore seated or unseated, as desired. That part a³ of the interior of the valve-casing which surrounds 90 the bushing a, is made to incline downwardly and outwardly as shown, so as to form a substantially conical surface. This inclined surface is therefore located opposite and below the valve-seat, and it is made 95 to terminate inwardly so as to bring the periphery of the valve vertically above same. Any dust or dirt which is discharged from the upper surface of the valve will therefore drop upon the inclined surface a³ 100 and will be carried downwardly and outwardly. One side of the casing is provided with an opening to which is suitably attached an intermediate nozzle member D, to whose outer surface is secured the nozzle 105 proper, D'. The inner surfaces of the nozzle and the member D are made continuous with each other, as shown, and the lower part of the member D is made continuous with the conical surface a³. By this means, 110 the dust and dirt deposited upon the said inclined surface will be carried around and

115

2
out of the nozzle without obstruction, as will be readily understood.

It will therefore be seen that by means of the above described construction, the flow of the gas from the main into the nozzle may be controlled as desired, and all dust and dirt which might tend to destroy the valve seat or interfere with the operation of the valve is automatically removed from the interior of the casing and its deleterious effect thus eliminated.

Having fully described my invention, what I claim therefore and desire to secure by Letters Patent is:—

- 15 1. In a device of the class described, the combination of a valve-casing provided with an upper gas-inlet, a gas-outlet, and a substantially horizontal valve-seat surrounding said inlet; a bell-valve below said seat and adapted to engage the same; means for actuating said valve from beneath said casing; and a nozzle connected with said outlet.
- 20 2. In a device of the class described, the combination of a valve-casing provided with an upper gas-inlet, a gas outlet, and a substantially horizontal valve-seat surrounding the inlet, that part of the valve-casing below and opposite the valve being removable, whereby such valve may be removed; means for actuating the valve; and a nozzle connected with said outlet.
- 25 3. In a device of the class described, the combination of a valve-casing provided with an upper gas-inlet, a gas-outlet, and a substantially horizontal valve-seat surrounding said inlet, that part of the valve-casing opposite and below said valve-seat being removable so as to form an opening through which said valve may be removed; a valve-40 stem connected with said valve seated in said removable casing portion; and means for actuating said stem longitudinally, so as to actuate said valve to seat and unseat; and a nozzle connected with said outlet.
- 35 4. In a device of the class described, the combination of a valve-casing forming a valve-chamber, and provided with an upper gas-inlet and a lateral gas-outlet; a valve within said chamber; and means for actuating said valve to seat and unseat; the

bottom of the interior of the valve-chamber being flush with said outlet, whereby the movement of the gas through the chamber will prevent the accumulation of solid matter therein.

55

5. In a device of the class described, the combination of a valve-casing forming a valve-chamber, and provided with an upper gas-inlet and a lateral gas-outlet; a valve within said chamber; means for actuating said valve to seat and unseat; the bottom of the interior of the valve chamber being flush with said outlet, whereby the movement of the gas through the chamber will prevent the accumulation of solid matter 60 therein; and a nozzle connected with said outlet and having its lower surface flush therewith.

65

6. In a device of the character described, the combination with a valve-casing provided with a gas outlet, a gas inlet, and a substantially horizontal valve seat surrounding said inlet, the bottom of the interior of the valve-casing being provided with a downwardly and outwardly inclined surface located vertically below and of greater diameter than said seat; of a bell-valve and means for seating and unseating same.

75

7. In a device of the class described, the combination of a valve-casing provided with a gas-inlet, a gas-outlet, a substantially horizontal valve-seat, and a downwardly and outwardly inclined surface opposite and below said seat; a bell-valve and means for seating and unseating same; said valve arranged to move in the space intermediate of said seat and surface, and having a downwardly and outwardly inclined upper surface terminating at the valve's periphery, the latter being located vertically above said 80 first-named downwardly and outwardly inclined surface; and a nozzle connected with said outlet and having its lower surface continuous with said last-named downwardly and outwardly inclined surface.

85

90 Signed by me, this 7th day of April, 1909.
ARTHUR G. MCKEE.
